(57) **CLAIM**

The ornamental design for a portable baby diaper changing pad, as shown and described.

DESCRIPTION

FIG. 1 is a top, front and right side perspective view of a portable baby diaper changing pad, showing my new design; FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the portable baby diaper changing pad in an alternate configuration and closed state; and,

FIG. 10 is an enlarged view of the portion labeled "10" in FIG. 2.

The dotted broken lines shown on the portable baby diaper changing pad depict stitching. And dot-dash broken line rectangular frames define the boundary of an enlarged view and form no part of the claimed design.
